UNITED STATES PATENT OFFICE.

WALTER C. WILLARD, OF GATES MILLS, OHIO.

SPRING-RETAINER FOR PUPPET-VALVES.

1,390,661.

Specification of Letters Patent. Patented Sept. 13, 1921.

Application filed August 27, 1920. Serial No. 406,375.

To all whom it may concern:

Be it known that I, WALTER C. WILLARD, a citizen of the United States, resident of Gates Mills, county of Cuyahoga, and State 5 of Ohio, have invented new and useful Improvements in Spring-Retainers for Puppet-Valves, of which the following is a specification, the principle of the invention being herein explained and the best mode in which 10 I have contemplated applying that principle, so as to distinguish it from other inventions.

My invention relates to devices for retaining the springs used for actuating puppet valves, its object being to produce a retaining 15 device simple in structure, economical of manufacture, efficient in the performance of its function, and one that may be assembled or taken down with facility.

The said invention consists of means hereinafter fully described and particularly set forth in the claims.

More specifically, said invention consists of a retainer member against which the spring is adapted to bear, which is secured in 25 place by a locking member engaging the valve stem, said locking member and retainer member having a universal bearing relation, whereby required adjustment of parts is automatically obtained.

30 The annexed drawing and the following description set forth in detail certain means embodying my invention, the disclosed means, however, constituting but one of the various mechanical forms in which the principle of the invention may be applied.

In said annexed drawing:

Figure 1 represents a fragmentary section of an automobile including a puppet valve and a retaining device embodying my invention, parts cut by the plane of section being shown in elevation.

Fig. 2 represents a plan of the retainer, showing the valve stem in section.

Fig. 3 represents an axial section of the 45 retaining or cup member.

Fig. 4 represents a bottom plan of such cup member.

Fig. 5 represents an axial section of one of the halves of the locking member.

50 Fig. 6 represents a plan, and Fig. 7 a side elevation of one of said halves.

In the illustrated embodiment of my invention, the valve stem 1 is formed near its end, with two parallel grooves 2, 2, of arcuate cross-section, as shown in Fig. 1. Into

these grooves are seated the inwardly projecting circumferential beads 3, 3, formed upon two halves of the locking member 4. These two halves are punched out so as to assume a shape such that the beads or arcs 60 3, 3, substantially fit the grooves 2, 2. Intermediate of these two beads, there is formed in each locking half an outwardly projecting rounded bearing surface 5, of greater diameter than the ends 6, 6, of the locking 65 member. Said two halves are each made slightly less than 180° in circumference, so that a small space remains between them, when assembled, as shown in Fig. 2, to allow for take-up due to possible inaccuracies of 70 production.

A retaining piece or cup 7 surrounds the end of the stem, the latter projecting through a central bottom aperture 8 formed in the cup and of a diameter slightly greater than that of the ends of the locking member 4 when assembled in place. This cup 7 is formed with a downwardly projecting circumferential flange 9, forming a seat for the end of the actuating spring 10; and is centrally depressed to form an interior conical bearing surface 11, which is engaged by the bearing surface 5 of the locking member.

It will be noted that the spring 10 through conical surfaces 11 exerts a wedging 85 action upon the two parts of the locking member 4, which causes them to clamp onto the valve stems. The heavier this pressure the tighter the two parts are held against the stem and the more secure is the engagement 90 of the beads 3, 3 with the grooves 2, 2. It will also be noted that the construction is such as not to produce a fixed axis of oscillation of the cup-member 7, but on the contrary the connection between said member 95 and the stem is of the character of a universal bearing.

The above-described construction lends itself to rapid production from low-priced materials inasmuch as the cup and locking 100 members may both be stamped from sheet metal. Furthermore, it permits of the elimination of defects incident to the adoption of the conventional key-slot, drilled holes or square grooves in the valve-stems, 105 and particularly those resulting from the heat-treating operation performed upon the valve stem after they are machined for receiving the retainers of the heretofore accepted types, and which have heretofore 110

arisen as a result of the presence of sharp angles incident to such valve-stem construction.

A further and important feature of the invention resides in the universal bearing relationship between the retainer and valve stem. This feature permits the parts when assembled to adapt themselves as to size and fit, to any inaccuracies of machined surfaces, and more particularly to the spring ends so as to relieve the valve stems from the side pressure and consequent wear otherwise present when spring ends are out of square with axis; and are self-aligning, while at the same time they are rigid as regards the retention of the spring.

In order to disassemble or take down the parts after the tapper or cam is disengaged, the spring is compressed, so as to relieve the pressure of the cup-member against the locking member 4. The two parts of the latter may be disengaged from the grooves 2, 2, and then removed from the cup-member. This permits the latter to be readily removed from the stem. In assembling the reverse operation is, of course, employed, all as will be readily understood by those skilled in the art.

What I claim is:

- 30 1. In a spring retainer for puppet valves, the combination with a cup-member adapted to receive the end of a coil-spring; of a locking member adapted to engage a valve stem and having a universal bearing relation with said cup-member.
2. In a spring retainer for puppet valves, the combination with a cup member having a concave surface and adapted to receive the end of a coil-spring, of a locking member

adapted to engage a valve stem and having a convex curved bearing surface engaging said concave surface of the cup-member.

3. In a spring retainer for puppet valves, the combination with a cup-member having a concave surface and adapted to receive the end of a coil-spring; of a two-part locking member formed with two interior beads adapted to engage respectively two grooves in a valve-stem, and with an exterior convex curved bearing surface engaging said concave surface of the cup-member.

4. In a spring retainer for puppet valves, the combination with a cup member of sheet metal pressed to form an interior concave surface and an exterior seat for the end of a coil-spring; of a two part locking member formed from sheet-metal pressed to form two interior beads and an intermediate exterior curved bearing surface; said beads adapted to engage grooves in a valve stem and said bearing surface adapted to engage said interior concave surface.

5. The combination with a valve-stem formed with two parallel circumferential grooves; of a spring retaining device through which said stem projects and comprising a cup-shaped member provided with an exterior spring seat, together with a locking member consisting of two similar parts each formed with two interiorly projecting semi-circular parallel circumferential beads and an intermediate circumferential depression forming the exterior rounded bearing surface; the latter surface engaging the interior surface of said cup-shaped member.

Signed by me, this 6th day of August, 1920.

WALTER C. WILLARD.
